J. J. HARPEL.

WASHING MACHINE FOR WASHING FABRICS.

APPLICATION FILED APR. 14, 1920.

1,426,185.

Patented Aug. 15, 1922.

UNITED STATES PATENT OFFICE.

JACOB J. HARPEL, OF ELMIRA, NEW YORK.

WASHING MACHINE FOR WASHING FABRICS.

1,426,185.

Specification of Letters Patent. Patented Aug. 15, 1922.

Application filed April 14, 1920. Serial No. 373,880.

To all whom it may concern:

Be it known that I, JACOB J. HARPEL, a citizen of the United States, residing at the city of Elmira, in the county of Chemung 5 and State of New York, have invented a new and useful Washing Machine for Washing Fabrics, of which the following is a specification.

The invention relates to washing machines 10 of the type designed to be operated by hand and embodying a plunger to be reciprocated vertically in a tub or like receptacle containing the suds water and fabric or articles to be laundered.

15 The invention relates chiefly to the general structure and arrangement of the parts and to the specific mountings and connections of certain elements, whereby provision is had for ready and convenient adjustment 20 without the use of tools or extraneous adjuncts.

Other objects and advantages will be apparent and suggest themselves as the nature of the invention is understood.

25 While the drawings illustrate an embodiment of the invention it is to be understood that in adapting the same to meet different conditions and requirements, various changes in the form, proportion and minor details of 30 construction may be resorted to without departing from the nature of the invention.

Referring to the accompanying drawings forming a part of the specification,

Figure 1 is a view in elevation of a washing machine embodying the invention, the outer portion of the handle being broken away.

Figure 2 is a detail view of the mounting to which the plates are connected and which 40 receives the operating spring, and

Figure 3 is a detail view of the upper end of the journal and the sleeve mounted thereon attached to the swinging arm.

45 Corresponding and like parts are referred to in the following description and designated in the several views of the drawings by like reference characters.

The plunger 2 is of inverted cup shape or pan formation and its lower edge is inturned 50 as indicated at 2^a to prevent splash and obviate injurious contact with the fabric or articles to be laundered. The stem 3 carrying the plunger 2 has the latter adjustably connected thereto whereby the effective 55 length of the stem 3 may be adjusted according to the depth of the tub or receptacle con-

taining the suds water and the fabric or articles being laundered. A clamp 9 rigidly attached to the plunger 2 is adjustable by means of a clamp screw 5, whereby to fasten 60 the plunger in the required adjusted position. Bars 7 and 8 are pivotally connected to the stem 3 at different points in the length thereof and occupy a substantially 65 parallel position. These bars are relatively 70 adjustable to admit of varying their length whereby the relative inclination of the stem 3 from the vertical may be varied according to the nature of the work and the relative 75 position of the parts comprising the machine. Each of the bars 7 and 8 comprises relatively sliding sections which are made 80 secure by means of a set screw 12. The opposite ends of the bars 7 and 8 are pivotally connected to a sleeve 1 from which extends 85 a projection 1^a in which is located a spring 6 adapted to engage and yieldably support the lower bar 8. The sleeve 1 is pivotally mounted upon a journal at the outer end of 90 an arm 30 which is mounted to swing horizontally about a vertical journal forming part of a clamp whereby the machine is made fast to the side of a tub or other receptacle 95 or support.

The clamp comprises a substantially U- 85 shaped frame, one element of which constitutes a jaw 14, the other element receiving a set screw 31 which is threaded 90 therein. An adjustable jaw 15 is slidably mounted upon the horizontal portion 16 95 of the frame and engages a portion thereof to prevent displacement, whereby loss of the adjustable jaw 15 is provided against.

The handle 32 which is preferably of wood 100 is provided at its inner end with a metal tip 33 which is curved and operates between extensions of the bar 8 to which the handle 32 is pivotally connected. A clamp screw 20 serves to draw the parts of the bar 8 together and clamp the handle and hold the 105 same in the required adjusted position. To guard against possible slipping the opposing side of the metal tip 33 and extensions of the bar 8 are formed with matching projections and depressions which preferably taper in form.

To avoid torsional strain as much as possible the vertical journal of the clamp receiving the swinging arms 30 is disposed to align as nearly as practicable with the side 110 of the tub or receptacle to which the clamp is attached. The bars 7 and 8 are spaced

apart and their manner of connection with the stem 3 and sleeve 1 results in the formation of a parallelogram which in the operation of the machine maintains the stem 3 of the plunger in substantially vertical position with the result that the plunger 2 in all positions remains parallel to a given position whereby the best results are attained in the operation of the machine.

Having thus described the invention, what I claim is:—

1. In a washing machine of the character specified, a plunger, relatively upper and lower bars pivotally connected at one end to the stem of the plunger and spaced apart and a support having the opposite end of the bars pivotally connected thereto, one of said bars comprising relatively adjustable sections whereby the inclination of the plunger within certain limits may be varied.
2. In a washing machine of the character specified, a plunger, relatively upper and lower bars pivotally connected to the stem of the plunger, a support having the opposite ends of the bars pivotally connected thereto, said support having a projection

and a spring carried by said projection and adapted to engage one of said bars to yieldably support the plunger in a given position.

3. In a washing machine of the character specified, a plunger, a bar having pivotal connection with the stem of the plunger and extending beyond the same a short distance, a handle having pivotal connection with the extension of the said bar, said handle having its inner end expanded vertically and means for clamping the expanded end of the handle to the bar whereby to hold the handle in the required adjusted position.

4. In a washing machine, an attaching member, an arm pivoted to the attaching member, a plunger having a stem, upper and lower bars pivotally connected at one end to the stem of the plunger, and a member having the opposite ends of the bars pivoted thereto and pivoted to the swinging end of the said arm, one of the bars being adjustable to vary the relative inclination of the plunger stem.

JACOB J. HARPEL.
